REEL

Arthur J. Junge, St. Louis, Mo.

Application July 18, 1935, Serial No. 32,012

7 Claims. (Cl. 242—86)

This invention relates to reels, and with regard to certain more specific features, to reels for hose and the like.

Among the several objects of the invention may be noted the provision of a hose reel particularly adapted for installation on tank trucks such as fuel oil trucks, which are used for delivering fuel oil to residences and the like; the provision of a reel of the class described which is adapted to fit 10 into a restricted space, but without reducing its hose capacity; the provision of a reel of the class described which is provided with a novel bearing system rendering it more easy and certain of operation; the provision, in a reel of the class 15 described, of means for manually turning the reel at a high mechanical advantage; the provision in a reel of the class described, of means for holding the reel against such displacements such as would be occasioned if the vehicle on which 20 the reel is mounted should encounter a sudden bump; and the provision of a reel of the class described wherein permanent connection of the inner end of the hose is maintained through winding and unwinding operations. Other objects 25 will be in part obvious and in part pointed out hereinafter.

The invention accordingly comprises the elements and combinations of elements, features of construction, and arrangements of parts which 30 will be exemplified in the structures hereinafter described, and the scope of the application of which will be indicated in the following claims.

In the accompanying drawing, in which is illustrated one of various possible embodiments of 35 the invention,

Fig. 1 is a side elevation of a reel embodying the present invention;

Fig. 2 is an ideal section taken substantially 40 along line 2—2 of Fig. 1 certain parts being broken away for clarity; and,

Fig. 3 is an end elevation of a portion of the reel of Fig. 1.

Similar reference characters indicate corresponding parts throughout the several views of 45 the drawing.

Referring now more particularly to Figs. 1 and 2, numerals 1 indicate a pair of angle-iron pieces which, arranged parallel to each other, form the base or support for the present invention. 50 At the opposite ends of the pieces 1, there are bolted bracket pieces 2, which serve to space the angle-iron pieces 1 apart in rigid assembly. Each bracket 2 comprises a pair of halves 3 and 4. The 55 halves 4 carry studs or bolts 5, which project through slots 6 in the opposite halves 3. By

means of the slots 6, lateral adjustments between the angle-iron pieces 1 may be effected for different width reels.

At the upper, outer extremities of each of the pieces 3 and 4, there is provided a bearing block 5 1. The two bearings 7 on each of the brackets 2 carry a shaft 8, at the ends of which are mounted rollers 9. The particular construction of the rollers 9 is apparent in Fig. 2, wherein it is seen that they comprise outer flanges 10 and a relatively narrow inner groove 11.

From the arrangement described, it will be seen that there are two rollers 9 at each end of the base, and that, considered from the side, there are two lateral pairs of rollers in the same 15 plane.

The rollers 9 constitute the supporting means for the reel proper, indicated by numeral 12. The reel proper comprises a pair of circular side plates 13 and 14 respectively, secured parallel to 20 each other, and coaxially, by a drum 15 centrally mounted therebetween. The drum 15 is cylindrical and is attached to the side plates 13 and 14 by inwardly extending flanges 16 and bolts 17. The diameter of the drum 15, which constitutes 25 the surface upon which the hose is reeled, is of course considerably less than the diameter of the side plates 13 and 14.

The drum 15 may comprise a single sheet or plate of steel or the like, bent to cylindrical form 30 and welded as indicated at numeral 18 in Fig. 1.

Carried on the outer base of the side plate 14 is a circular ring gear or rack 19. The rack 19 comprises a flat steel annulus 20 and evenly-spaced cylindrical pins 21 spacing said annulus 35 20 from said plate 14. The pins 21 are desirably press-fitted or welded to both the plate 14 and to the annulus 20. The even spacing of the pins 21 permits them to be used as the equivalent of gear teeth for the driving mechanism for the reel. 40

Bolted to the outside of the left-hand angle-iron piece 1 is a bracket 22, which has approximately a U-shape and is preferably made of welded angle-iron. A flat portion 23 at the top of the bracket 22 has bolted thereto a bearing 45 block 24, in which is borne a shaft 25. The inner end of the shaft 25 carries a pinion 26, the teeth of which are of suitable shape and size to engage with the pins 21 of the ring gear 19 heretofore described. On the outer end of the shaft 25 there is 50 removably secured a crank handle 27. By turning the crank 27 it will be seen that the reel as a whole is driven to rotate on the rollers 9. Because the point of engagement of the pinion 26 with the ring gear 19 is spaced at a considerable distance 55 from the center of rotation of the reel, and be-

cause of the relative diameters of said pinion 26 and the ring gear 19, it will be seen that a considerable mechanical advantage is obtained in driving the reel to rotate. This of course is of benefit in reeling up the hose or the like onto the reel.

In the center of the side plate 14 is provided a circular opening 28. The opening 28 is for the purpose of inserting the connecting mechanism 10 to which the inner end of the hose on the reel is connected. The structure of this mechanism will be seen more particularly in Fig. 2. It comprises a dead-end flange 29 which is bolted to the center of side plate 13, on the inside thereof. Screwed 15 into the flange 29 is a short length of pipe 30, and to the opposite end of the pipe length 30, is screwed a Y-coupling 31, the side outlet portion of which is at an angle of 45 degrees to the run of the fitting. A short nipple 32 connects the 20 side outlet of the fitting 31 to a 45-degree L 33, in the other end of which is in turn screwed a nipple 34. A hole 35 is provided in the drum 15 in the region of the nipple 34, and through this hole, there is screwed on the nipple 34 a 90-degree L 36. To the L 36 there is attached, by 25 means of a suitable coupler 31, the inner end of the hose 38 which it is desired to reel on the device. A hand hole 60 (see Fig. 1) is desirably provided in the side plate 14 in order to permit 30 the insertion of a wrench or the like to tighten the connection of the hose to the L 36.

Returning to the Y-fitting 31, the other side of the run of the fitting receives the cylindrical end 39 of a swivel union 40. The end 39 is supported in a block 41 which is in turn carried on the upper or inner end of a plate 42 of sector shape. The plate 42 is supported on the side plate 14 by means of certain of the bolts 47, indicated by numerals 43, which have long collars 44 spacing said sector plate 42 inwardly from the side plate 14. The swivel union 40 has an elbow extension 45 on its other side, which is connected by a coupling 46 to a pipe 47. The pipe 47 communicates with the source of fluid in consideration. For example, if the reel is mounted on a tank truck, the pipe 47 connects to the tank.

It will be seen that the entire assembly comprising the elements 29, 30, 31, 32, 33, 34, 35, 36, 39 and 40, rotates together with the reel as the 50 same is turned by means of the crank 27. The swivel union 40, however, permits the assembly 45-46-47 to remain stationary while the reel is being turned. This is of considerable advantage as it means that at no time during the use 55 of the hose 38 need it be unfastened from the reel. In other words, when a delivery is to be made, all the operator needs to do is to unreel the hose from the drum, and immediately commence pumping liquid through it. In prior devices of 60 this general type, it was ordinarily necessary to unreel the entire hose, connect the near end to the tank, and then commence pumping. When the hose is to be re-reeled, as after a delivery has been made, again no connection nor disconnection need be effected, but by merely turning the 65 crank 47, the entire hose is reeled on the drum, and remains in position for the next delivery.

Encircling the upper half of the peripheries 70 of the side plates 13 and 14 is a strap 48 which has a U-shaped cross-section as shown in Figure 2. The left-hand ends of the strap 48 are flattened as indicated at numeral 49 and have slots 50 provided therein. Through the slots 50 pass studs or bolts 51 threaded into the angle-iron pieces 1. By loosening the studs 51, the

tension in the strap 48 can be adjusted, as will be seen. The other ends 52 of the strap 48 are likewise flattened. However, instead of being attached directly to the angle-iron pieces 1, the ends 52 are attached to the offset portion 53 (see Fig. 3) of a shaft 54 which is carried in upwardly extending standards 55 bolted to the opposite ends of the angle-iron pieces 1. The left-hand end of the shaft 54 carries a lever 56 thereon. The lever 56 has a handle 57 including a spring-catch mechanism 58. The mechanism 58 is arranged to engage a suitable opening 59 in the left-hand standard 55. The purpose of this arrangement is that by turning the lever 56, the offset portion 53 is angularly moved, thereby bringing a greater or less tension on the straps 48. By this means, the straps 48 may be loosened to the point that they do not interfere with ready rotation of the drum when the hose is being either reeled in or reeled out, but at the same time the straps 48 may be tightened in such a manner that they constitute brakes against rotation of the drum. In addition to acting as brakes against the rotation of the drum, the straps 48 retain the drum and its assembly on the rollers 9. That this arrangement is particularly effective will be seen when it is considered that the principal use of the present invention is on the rear platform of automobile tank trucks, which are frequently obliged to go over rough roads with considerable jolting. Lacking the retaining strap 48, it might frequently be possible for the side plates 13 and 14 to jump off the rollers 9, and thereby cause trouble in the operation of the reel.

As has been indicated, the tension in the straps 48 may also be regulated in a semi-permanent manner by means of the slots 50 and bolts 51. It has been found adequate for breaking and locking purposes, to have a total linear pull or 40 displacement, occasioned by the offset portion 53, of about one inch, when the side plates 13 and 45 14 are of the order of three feet in diameter.

When the present invention is installed on an 45 automobile tank truck. In the manner heretofore intimated, it may be made of such a dimension that it readily fits into the cabinet usually provided on the rear end of such trucks, without rebuilding the end platform of the truck. Under 50 these conditions, it is customary for the crank 27 and the lever 56, together with the spring-pressed mechanism 58-59, to be located on the outer wall of the cabinet. This provides for ready availability of the device to the driver of 55 the tank truck.

The present invention is ideally adapted for such installations inasmuch as it presents a reel, substantially the entire width of which is available for the storage of hose. In prior reels where the bearing system was such that the reel was borne on a central bearing as distinguished from the rollers 9 provided in the present invention, this efficient utilization of space was not possible inasmuch as the central bearings of necessity had to extend laterally beyond the confines of 60 the reel itself.

In view of the above, it will be seen that the several objects of the invention are achieved and other advantageous results attained.

As many changes could be made in carrying out the above constructions without departing from the scope of the invention, it is intended that all matter contained in the above description or shown in the accompanying drawing shall 70 75

be interpreted as illustrative and not in a limiting sense.

I claim:

1. A hose reel comprising a cylindrical drum, circular side plates laterally terminating said drum and providing a trough for receiving the hose, a base, four rollers provided on said base, two on each side thereof, each pair of rollers receiving and supporting one of said side plates, means supported on said base for driving the reel to rotate on said rollers comprising a ring gear mounted on the outer face of one of said side plates, a pinion engaging said ring gear, and a crank for turning said pinion, the teeth of said ring gear comprising pins separately mounted on one of said side plates.

2. A hose reel comprising a cylindrical drum, circular side plates laterally terminating said drum and providing a trough for receiving the hose, a base, four rollers provided on said base, two on each side thereof, each pair of rollers receiving and supporting one of said side plates, means supported on said base for driving the reel to rotate on said rollers, and means engaging the upper peripheries of said side plates and attached at their ends to said base, whereby said side plates are prevented from leaving said rollers.

3. A hose reel comprising a cylindrical drum, circular side plates laterally terminating said drum and providing a trough for receiving the hose, a base, four rollers provided on said base, two on each side thereof, each pair of rollers receiving and supporting one of said side plates, means supported on said base for driving the reel to rotate on said rollers, straps engaging the upper peripheries of said side plates and attached at their ends to said base, whereby said side plates are prevented from leaving the rollers, and means for increasing and decreasing the tension in said straps whereby said side plates are permitted freely to rotate or are braked.

4. A hose reel comprising a cylindrical drum, circular side plates laterally terminating said drum and providing a trough for receiving the hose, a base, four rollers provided on said base, two on each side thereof, each pair of rollers receiving and supporting one of said side plates, means supported on said base for driving the reel to rotate on said rollers, straps engaging the upper peripheries of said side plates and attached

at their ends to said base, whereby said side plates are prevented from leaving the rollers, means for increasing and decreasing the tension in said straps whereby said side plates are permitted freely to rotate or are braked, said last-named means comprising a shaft having an offset portion engaging one end of each of said straps, and means for rotating said shaft.

5. A hose reel comprising a cylindrical drum, circular side plates laterally terminating said drum and providing a trough for receiving the hose, a base, four rollers provided on said base, two on each side thereof, each pair of rollers receiving and supporting one of said side plates, means supported on said base for driving the reel to rotate on said rollers, and straps engaging the upper peripheries of said side plates and attached at their ends to said base, whereby said side plates are prevented from leaving said rollers, said straps comprising strips of metal having a U-shaped cross section, the peripheries of said plates being received in the troughs of the said U-shapes.

6. A hose reel comprising a cylindrical drum, circular side plates laterally terminating said drum and providing a trough for receiving the hose, a base, four rollers provided on said base, two on each side thereof, each pair of rollers receiving and supporting one of said side plates, means supported on said base for driving the reel to rotate on said rollers comprising a ring gear mounted on the outer face of one of said side plates, a pinion engaging said ring gear, a crank for turning said pinion, said ring gear comprising a flat annulus, and evenly spaced pins supporting said annulus on the side of and concentrically with one of said side plates, said pins comprising the teeth of said ring gear.

7. A hose reel comprising a cylindrical drum, circular side plates laterally terminating said drum and providing a trough for receiving the hose, a base, four rollers provided on said base, two on each side thereof, each pair of rollers receiving and supporting one of said side plates, and means separate from said rollers frictionally engaging said side plates to prevent them from leaving the rollers, said last-named means being adjustable, whereby they are also adapted to exert an adjustable braking action on said side plates.

ARTHUR J. JUNGE. 50
